[57] CLAIM

The ornamental design for a vehicle washing sponge, as shown and described.

DESCRIPTION

FIG. 1 is a front elevational view of the vehicle washing sponge of the present invention;

FIG. 2 is a back elevational view of the vehicle washing sponge of FIG. 1;

FIG. 3 is a left side elevational view of the vehicle washing sponge of FIG. 1;

FIG. 4 is a right side elevational view of the vehicle washing sponge of FIG. 1;

FIG. 5 is a top plan view of the vehicle washing sponge of FIG. 1; and,

FIG. 6 is a bottom plan view of the vehicle washing sponge of FIG. 1.

The handle is shown broken away in all of the views to indicate determinate length.
